O-RING MEASURING GAUGE

James S. Bogart, Farmington Hills, Mich., and John M. Wilcox, Columbia, S.C., assignors to Federal-Mogul Corporation, Southfield, Mich.

Filed Oct. 29, 1974, Ser. No. 518,611

Term of patent 14 years

Int. Cl. D10—04

U.S. Cl. D10—70

FIG. 1

FIG.2

FIG.3

FIG.4

FIG.5

FIG.6

FIG.7

FIG.8

FIG. 1 is a front perspective view of an O-ring measuring gauge showing our new design in a partially extended position;

FIG. 2 is a left end elevational view thereof;

FIG. 3 is a right end elevational view thereof;

FIG. 4 is a front elevational view thereof;

FIG. 5 is a top plan view thereof;

FIG. 6 is a rear elevational view thereof with a cutaway portion illustrative of the notch contours;

FIG. 7 is a bottom plan view of the outer or right side member of FIG. 1; and

FIG. 8 is a bottom plan view of the inner or left side member of FIG. 1.

We claim:

The ornamental design for an O-ring measuring gauge, substantially as shown and described.
